UNITED STATES PATENT OFFICE.

CHARLES SPURGES, OF DE KALB, ILLINOIS.

DESIGN FOR AN AUTOMOBILE BODY.

Application filed September 7, 1926. Serial No. 18,997. Term of patent 14 years.

To the Commissioner of Patents:

Be it known that I, CHARLES SPURGES, a citizen of the United States, residing at De Kalb, Illinois, have invented a new, original, and ornamental Design for an Automobile Body, of which the following is a specification, reference being had to the accompanying drawing, forming part thereof.

I claim:

The ornamental design for an automobile body, as shown.

CHARLES SPURGES.
